DUAL SPRING TAKE-UP REEL

Louis Leroy, Altadena, Calif., assignor to McCaffrey-Ruddock Tagline Corporation, Los Angeles, Calif., a corporation of California

Application June 27, 1949, Serial No. 101,517

8 Claims. (Cl. 242—108)

1

This invention relates to reels for automatically maintaining a line, cable or the like under substantially constant tension and free of slack as the required length of the line varies; more particularly, it relates to spring means for driving such reels.

It is an object of this invention to provide an improved spring driven reel of this type.

Spring driven reels or the like of the type under discussion are extensively used in connection with various types of material handling equipment, cranes, hoists and the like, which often form an integral part of a plant. Thus, costly shut-downs thereof will result if the material handling equipment is rendered inoperative. It is thus of importance that the reel be of rugged construction and otherwise arranged to reduce possible reel failures and ensuing shut-downs from this cause, or at least to minimize their duration. Since the driving spring is the most likely cause of failure in the reel, it is another object of this invention to provide a spring driven reel including a spare or stand-by spring for operating the reel in lieu of the usual driving spring.

It is another object of this invention to provide an automatic take-up reel having a pair of driving springs either or both of which may be connected in driving relation with the reel.

It is another object of this invention to provide an automatic take-up reel having a stand-by driving spring arranged to be connected in driving relation with the reel in a simple and expeditious manner.

It is still another object of this invention to provide such a reel wherein the main driving spring may be easily replaced while the stand-by spring is connected to drive the reel.

This invention possesses many other advantages and has other objects which may be made more easily apparent from a consideration of one embodiment of the invention. For this purpose there is shown a form in the drawings accompanying and forming part of the present specification. This form will now be described in detail, illustrating the general principles of the invention; but it is to be understood that this detailed description is not to be taken in a limiting sense, since the scope of the invention is best defined by the appended claims.

In the accompanying drawings:

2

Figure 1 is a longitudinal axial section, partly in elevation, showing an automatic take-up reel incorporating the features of the invention;

Figure 2 is a fragmentary cross section, taken substantially as indicated by line 2—2 of Figure 1;

Figure 3 is a fragmentary sectional view on an enlarged scale, taken substantially as indicated by line 3—3 on Figure 1, and showing in elevation one of the driving springs and its method of anchoring;

Figures 4 and 5 are sectional views similar to Figure 1, but showing different operating positions of the parts.

Referring to Figure 1, the reel device is shown by way of example as incorporating a double winding drum 1 of the type disclosed in U. S. Patent Number 2,303,002, granted to William Ruddock on November 24, 1942, and entitled "Tagline Device," wherein one section, as 2 of the

winding drum 1, accommodates a tagline L or the like and the other section 3 accommodates an electrical conducting cable C for supplying power to a lifting magnet or the like, being connected with the power lines by the aid of a slip ring structure 4 and leads (not shown). The line L and the cable C are spooled on the respective drums 2 and 3 so that, as viewed from the right, Figure 1, unwinding of the line and cable will cause counterclockwise rotation of the drums.

Referring in detail to the drawings, the reel device comprises a support structure 10 providing a pair of elongated tubular housing members 11 and 12 supported in spaced parallel relation by filler blocks 13 and adapted to be secured to a derrick boom, crane frame, or other suitable structure (not shown) by the aid of mounting pads, one of which is shown at 14. Axially extending members 15 and 16 are rotatably supported respectively in the housings 11 and 12 by the aid of bearing structures 17 and 19, and 18 and 20, respectively, at the opposite ends of the housings 11 and 12.

The rotatable member 15 has an intermediate tubular portion 15-a with reduced end portions 15-b and 15-c which project respectively through the bearing structures 17 and 19, the projecting portion 15-b having the drum 1 mounted thereon for rotation therewith. The bearing structure 17 serves as a closure for the adjacent end of housing 11 by means of an annular flange

17-a which is of somewhat greater diameter than the housing 11 to accommodate bolts 21 which secure the bearing structure in place. As shown, the bolts 21 also mount a protective enclosure 4-a for the slip ring structure 4.

The bearing structure 19 at the opposite end of the housing 11 includes a bearing element 23 which similarly serves as a closure by the aid of an annular flange 23-a attached to a flange 11-a on the housing 11 by bolts 24. The bearing element 23 has a bore 23-b of substantially greater diameter than the end portion 15-c of the rotatable member 15, a bushing or sleeve 25 being interposed between said end portion and said bore. The sleeve 25 is independently rotatable with respect to both said end portion 15-c and bore 23-b, and is axially restrained by a shoulder 25-a and a collar 26 engaging the opposite ends of the element 23.

A coiled spring 27 is accommodated in the 20 housing 11 and about the rotatable member 15, one end 27-a being restrained against rotation by being connected to the support 10, the other end 27-b being connected to the bushing 25 to impart rotation thereto with respect to the support 10.

Means are provided for connecting the bushing 25 and member 15 in driving relation. Thus, the outer end of the bushing 25 is formed with a diametral slot 25-b (see Figure 2) adapted to be engaged optionally by lugs 28-a provided on a member 28 splined on the reduced portion 15-c of the member 15 by a key 29-a, and secured in axially adjusted position by a set screw 30.

The rotatable member 16 comprises an intermediate tubular portion 16-a with an inserted element 16-b at one end providing a reduced bore 16-d, and a reduced portion 16-c at the other end which projects through the bearing structure 20. The bearing structure 18 comprises a cylindrical projection or pintle 18-a, which engages the bore 16-d, and is secured to a plate 18-b closing the adjacent end of the housing 12. The bearing structure 20 comprises a hub 20-a rotatably supporting the reduced portion 16-c of the member 16 and an annular flange 20-b serving as a closure for the housing 12 and attached to a flange 12-a thereon as by bolts 32.

A coiled spring 35, substantially identical with the spring 27, is accommodated in the housing 12 and about the rotatable member 16, one end 35-a being restrained against rotation by being connected to the support 10, the other end 35-b being connected to the member 16 to impart rotation thereto with respect to the support 10. Thus, the opposite ends respectively of springs 27 and 35 are connected to the support 10.

A gear wheel 36 is detachably secured on the reduced portion 16-c of the member 16 as by a washer 37 and screw 38 threaded into the portion 16-c, being constrained to rotate therewith by key 39. Gear 36 is adapted to engage a similar gear 29 formed on the clutch member 28, the arrangement being such that by appropriately positioning the gears 36 and 29 on their respective rotatable members 15 and 16, either or both springs 27 and 35 may be connected optionally in driving relation with the drums 2-3. A protective cover 40 may be provided for the gears, if desired, being supported by the aid of bolts 24 and 32.

With the gears 36 and 29 engaged and clutch member 28 and bushing 25 disengaged, as shown in Figure 1, spring 35 is connected in driving relation with the drum 1, spring 27 being dis-

connected. Thus, rotation of the drum 1 in line unwinding counterclockwise direction will be transmitted by member 15, clutch and gear member 28-29 and gear 36 to member 16, which will be rotated clockwise, due to the gearing 29, 36, and tighten the spring 35. Spring 35 opposes rotation of the drum in line unwinding direction and causes the drum to turn in the opposite direction and wind the line upon a reduction of the tension therein. Accordingly, the tension in the line L is at all times determined by the force of the spring 35.

This is the normal operating arrangement of the device, and brief consideration will show, that in the event of failure of spring 35, the spring 27 may be readily connected to operate the drum 1. For this purpose, it is only necessary to remove the gear and clutch member 28-29 and replace it in reversed position with clutch member 28 in engagement with the bushing 25. This obviously requires removal of the retaining washer 41 and appropriate manipulation of the set screw 30.

An important advantage of the arrangement is that the spring 35 can be replaced without taking the reel out of service for more than a brief interval required to remove the gear 36, the teeth of which must pass between the teeth of gear 29 as the gear 36 is moved axially along the reduced portion 16-c. Thereafter the gear cover 40 is removed, and the bearing structure 20 removed from the housing 12, allowing removal and replacement of the spring 35. As shown in Fig. 5, the gear members 29 and 36 of the clutch may be maintained in connection by sliding member 29 back and away from bushing 25 which latter engages spring 27, thereby disengaging spring 27 and driving the assembly only through the spring 25. Thus, operation of the reel without a second or stand-by spring being readily available is necessary for only a short time.

With the gears 36 and 29 disengaged and clutch member 28 engaging the bushing 25, as shown in Figure 4, spring 35 is disconnected and spring 27 connected in driving relation with the drum structure 1. Thus, rotation of the drum 1 in line winding direction (counterclockwise) will be transmitted by member 15 to the bushing 25, tightening the spring 27 and tensioning the line as before. The spring 27 thus serves as a standby to be brought into operation upon failure of the spring 35.

If increased tension in excess of that obtainable with either spring alone is required the parts may be arranged so that both springs 27 and 35 are active, their forces being in assisting relation. Thus, as shown in Figure 5, the clutch and gear member 28-29 is positioned to engage the bushing 25, thus connecting the spring 27 in driving relation with member 15 and the drum structure 1 and gear 36 is positioned to engage gear 29, thus connecting the member 16 and spring 35 also in driving relation with the member 15 and the drum structure. Rotation of the drum 1 in line unwinding direction will thus wind both springs 27 and 35 simultaneously and be opposed by their combined tensions.

As pointed out in the previously identified patent, it is desirable to protect the springs 27 and 35 against excessive unwinding movement, such as would result from spinning of the drum 1 caused by its inertia upon breakage or disconnection of the line L. Thus, as shown in Figure 3, the ends of the spring 27 are formed as oppositely facing hooks 43 and 44 adapted to engage respec-

tively the faces 45-a and 46-a of the driving lugs or projections 45 and 46 formed respectively on the bearing member 17 and the bushing 25. These faces 45-a and 46-a are preferably rounded to retain the hooks 43 and 44 in place, the opposite end portions 45-b and 46-b sloping toward the adjacent ends of the housing 11.

Thus, rotation of the member 15 in the direction indicated by the arrow Figure 3 will cause the hooks 43 and 44 to engage the end faces 45-a and 46-a, and wind and tension the spring 27. Rotation of the member 15 in the opposite direction will relieve the tension in the spring and thereafter cause disengagement of the hooks 43 and 44 which will ride past the lugs on the sloping end portions 45-b and 46-b respectively.

Spring 35 is detachably connected to the support 10 and the rotatable member 16 in a similar manner. Thus, hooks 47 and 48 formed on the ends of the spring 35 engage respectively the lugs or projections 49 and 50 on the bearing hub 20-a and on the insert 16-b, upon rotation of the member 16 in a clockwise direction as viewed from the right Figure 1, and disengage upon rotation in the opposite direction, after the tension in the spring has been released.

I claim:

1. In a spring driven reel device: a support; a winding drum; a member carrying said drum; means rotatably mounting said member on said support including an element interposed between said member and said support and rotatable independently of said member; a coiled spring connected at one end to said support and at the other end to said element; and means for optionally connecting said member and said element in driving relation.

2. In a spring driven reel device: a support including an elongated housing; a member extending axially in said housing; bearing means rotatably supporting said member adjacent the ends of said housing respectively and through which said member extends; a winding drum fixed on said member exteriorly of said housing and adjacent one end thereof; the bearing means adjacent the other end of said housing including an element secured to the housing, and a bushing freely rotatable in said element and in which said member rotates; a coiled spring in said housing, one end of said spring being restrained against rotation, the other end being connected to said bushing; and means for optionally connecting said bushing and said member in driving relation.

3. In a spring driven reel device provided with a pair of coiled springs to drive a reel; a support; a winding drum; a member carrying said drum; means rotatably mounting said member on said support including an element interposed between said member and said support and rotatable independently of said member; means restraining one end of each of said springs against rotation, means connecting the other end of each of said springs respectively in driving relationship with said drum and said element, and means for optionally connecting said member and said element in driving relationship.

4. In a spring driven reel device provided with a pair of coiled springs to drive a reel; a support; a winding drum rotatably mounted on said support; a pair of independently rotatable elements mounted on said support; each spring of said pair of coiled springs being connected at one end to said support; the other ends of said springs being connected respectively to said elements; and

means for optionally disconnecting one of said elements and said drum from driving relation.

5. In a spring driven reel device provided with a pair of coiled springs to drive a reel; a support including an elongated housing for each spring; a member extending axially in each of said housings; bearing means rotatably supporting said members adjacent the ends of said housings and through which said members extend; a winding drum exteriorly of one of said housings and adjacent one end thereof; the bearing means secured to the other end of each of said housings including an element secured to said housing and in one of said housings, a bushing freely rotatable in said element in which bushing said member rotates; one end of each of said coiled springs being restrained against rotation; the other end of each of said coiled springs being connected to the respective bushing; and means for optionally disconnecting a member from driving relation with the other end of one of said coiled springs.

6. In a spring driven reel device provided with a pair of coiled springs to drive a reel; a support; a pair of members mounted for independent rotation thereon; a winding drum mounted on one of said members; clutch means for optionally connecting said members in driving relation; means connecting one end of each of said springs to said support; means connecting the other end of each of said springs to said members respectively to cause rotation thereof relative to said support by the influence of said springs; at least one of said connecting means for each spring including means for releasing the associated spring upon rotation of the associated member ahead of the spring and operating to reconnect said spring upon rotation of said associated member in the opposite direction.

7. In a spring driven reel device provided with a pair of coiled springs to drive a reel; a support including a pair of elongated housings; a member extending axially in each of said housings; bearing means rotatably supporting said members adjacent to the ends of each of said housings, said members extending through the bearing means at a corresponding end of each housing, one of said members also extending through the bearing means at the opposite end of the housing; a winding drum mounted on said one member exteriorly of said opposite end of the housing; the bearing means adjacent the other end of said housing including an element secured to the housing and a bushing freely rotatable on said housing in which said one member rotates; one end of each of said coiled springs being restrained against rotation, the other ends of said springs being connected respectively to said bushing and to the member in the other housing; clutch means for optionally connecting said members in driving relationship and for optionally connecting said bushing and the member mounting the drum in driving relation, whereby one or both of the springs may be connected in driving relation with the drum.

8. In a spring driven reel device provided with a pair of coiled springs to drive a reel; a support including a pair of elongated housings; a member extending axially in each of said housings; bearing means rotatably supporting said members adjacent the ends of said housings; said members extending through the bearing means at a corresponding end of said housing, one of said members also extending through the bearing means at the opposite end of one housing; a winding drum mounted on said one member

exteriorly of said opposite end of said one housing; one end of each of said coiled springs being restrained against rotation; the other end of one of the coiled springs being connected to the other member; means including gearing means on said members for optionally connecting said one member in driving relation with the other member or with the spring in said one housing, the gearing means on the other of said members being demountable; and means detachably securing the bearing means for the said other member which is adjacent the gearing to the other housing to permit removal and replacement of

the coiled spring connected to said other member, independently of said one member.

LOUIS LEROY.
